UNITED STATES PATENT OFFICE.

HARRY H. WEST, OF PLYMOUTH, PENNSYLVANIA.

DESIGN FOR HOSE.

46,627.

Specification for Design.

Patented Nov. 3, 1914.

Application filed April 6, 1914. Serial No. 830,059. Term of patent 14 years.

To all whom it may concern:

Be it known that I, HARRY H. WEST, a citizen of the United States, and a resident of Plymouth, in the county of Luzerne and State of Pennsylvania, have invented a new, original, and ornamental Design for Hose, of which the following is a specification, reference being had to the accompanying drawing, forming part thereof.

Figure 1 is a side elevation of a hose showing this new design, said hose being shown disposed on a display form: Fig. 2 is a similar view of the hose with a shaping board disposed therein.

Referring more particularly to the drawing this new design comprises a hose 1 having a reinforced foot and heel, the reinforce 2 of the foot extending over about three-fourths of the width thereof with an auxiliary reinforce 3 at the toe extending across

the top of the foot at the rear of the normally reinforced toe 4. The foot reinforce 2 and heel reinforce 5 are of the same height, and a narrow reinforce 6 is provided above the heel at the rear of the hose thus forming in conjunction with the heel reinforce 5 a step-like formation. From the drawing it will be readily seen that the contour of the reinforced portions of the hose presents lines which are pleasing to the eye and tend to render to the hose an unusually attractive appearance.

I claim:

The ornamental design for hose, as shown and described.

HARRY H. WEST.
